[57] **CLAIM**

The ornamental design for a function selector for a computer printer, as shown and described.

DESCRIPTION

FIG. 1 is a front elevational view of a function selector for a computer printer showing our new design;

FIG. 2 is a top plan view thereof;

FIG. 3 is a bottom plan view thereof;

FIG. 4 is a right side elevational view thereof, the left side elevational view is a mirror image thereof;

FIG. 5 is a rear elevational view thereof; and

FIG. 6 is an enlarged front side perspective view thereof.

FIG. 1

FIG. 2

FIG. 3

FIG. 4

FIG. 5

FIG. 6
